(57) CLAIM

The ornamental design for a pendant, as shown and described.

DESCRIPTION

1. Pendant

1.1 : Perspective view 1

1.2 : Perspective view 2

1.3 : Front

1.4 : Back

1.5 : Top

1.6 : Bottom

1.7 : Right

The broken lines shown illustrate portions of the pendant and form no part of the claimed design. The left view is omitted because it is mirror image of the right view.
